UNITED STATES PATENT OFFICE.

SINGLETON D. HATCHER, OF CLEVELAND, OHIO, ASSIGNOR OF TWO-THIRDS
TO FRANK A. EDMONDS AND WILL F. CROLEY, OF SAME PLACE.

BEVEL-SQUARE.

SPECIFICATION forming part of Letters Patent No. 451,659, dated May 5, 1891.

Application filed July 23, 1890. Serial No. 359,605. (No model.)

To all whom it may concern:

Be it known that I, SINGLETON D. HATCHER, of Cleveland, in the county of Cuyahoga and State of Ohio, have invented certain new and useful Improvements in Adjustable Squares; and I do hereby declare the following to be a full, clear, and exact description of the invention, such as will enable others skilled in the art to which it pertains to make and use the same.

My invention relates to improvements in adjustable squares in which the two arms thereof are rabbeted and pivotally secured to each other, so that the short arm may be folded against the long arm for convenience in storing or in carrying the square. Positive stops are provided for adjusting the two arms in position, respectively, at angles of forty-five degrees and of ninety degrees to each other, and a scale is sometimes provided for convenience in adjusting the arms at intermediate angles.

In the accompanying drawings, Figures 1 and 4 are views showing different working positions of the square. Fig. 2 is an edge view, partly in section, showing the construction of the joint. Fig. 3 shows the short arm of the square detached.

A represents the long arm of the square, and B the short arm. The long arm has a short member A', square in plan and preferably integral therewith, the dimensions thereof in either direction corresponding with the width of arm B. Arm B and member A' are joined together, as shown more clearly in Fig. 2, and pivotally secured by means of a rivet C, the two corners a and b being rounded, so that arm B may fold against arm A, as shown in dotted lines, Fig. 4. The other corners a' and b' are left full and square, so as to abut the opposing shoulders, and thereby form stops when arm B is extended exactly at right angles to arm A. Member A' is provided with two holes c and d of equal dimensions, and arm B has corresponding holes 1, 2, 3, 4, and 5, all of these holes being screw-threaded and countersunk, and screws e and f are provided for engaging the respective holes flush with the surface of the square, the arrangement of these holes being such that when arm B is extended at a right angle to arm A holes 4

and 3 in arm B will register, respectively, with holes c and d in member A', and when arm B is collapsed or folded against arm A holes d and c in member A' will register, respectively, with holes 1 and 5 in arm B. If it is desired to have a miter-square, arm B is but partially folded—that is, until hole 2 of said arm registers with hole d of member A', when arm B will just be at an angle of forty-five degrees to arm A. By tightening one or both of screws e and f in the respective holes that register the square may be secured in any of the adjustments aforesaid. By providing arm B with additional holes the square may be made capable of intermediate adjustments, and it will be observed that the screws need not be removed in making the different adjustments, but need only be withdrawn from the holes in arm B, and hence there is no liability of the screws becoming lost. Although assisting screw f in retaining the square in its folded or extended position, as shown, screw e might be dispensed with.

A modification is shown in Fig. 4, wherein arm B is provided with a curved slot i, in which operates the shank of a thumb-screw I, and arm A is provided with a mark a² and member B is provided with a scale b² for convenience in setting the square, and hence it will be observed that by adjusting the set-screws in slot i the square may be accurately set at an angle of forty-five degrees or at any intermediate angle.

The ordinary carpenter's square is very inconvenient in carrying it about with a small kit of tools—for instance, in doing job-work, and it is also a cumbersome device to store away; but with my improved construction, whereby the two arms of the square may be collapsed or folded, these objectionable features are entirely overcome; also, it is a great convenience in having a square that can be manipulated so as to be used for a miter-square and for a general bevel-square, so that a carpenter need only to carry the one tool for all these purposes.

What I claim is—

1. An adjustable square having the two arms thereof rabbeted and pivotally secured to each other, so that they may be folded, positive stops being provided, substantially as

shown, for adjusting the arms of the square in position at angles of different degrees to each other, substantially as set forth.

2. An adjustable square comprising two arms, one of which has a short member pivotally secured to the other arm, whereby the latter may be folded against the arm having the short member, a series of threaded holes in said short member and one or more corresponding threaded holes in the collapsible or folding arm, the arrangement being such that the holes in the folding or collapsible arm will register with holes in the short member of the other arm when the square is set, re-

spectively, with its arms at an angle of forty-five or ninety degrees with each other, and one or more screws adapted to engage the registering holes and retain the square in the adjustment desired, substantially as and for the purpose set forth. 15

In testimony whereof I sign this specification in the presence of two witnesses this 11th day of July, 1890. 20

SINGLETON D. HATCHER.
